UNITED STATES PATENT OFFICE.

PETER F. AUGENBRAUN, OF STAMFORD, CONNECTICUT, ASSIGNOR TO THE YALE & TOWNE MANUFACTURING COMPANY, OF STAMFORD, CONNECTICUT.

PIN-TUMBLER LOCK.

1,422,518.

Specification of Letters Patent. Patented July 11, 1922.

Application filed September 2, 1921. Serial No. 497,899.

To all whom it may concern:

Be it known that I, PETER F. AUGENBRAUN, a citizen of the United States, and a resident of Stamford, in the county of 5 Fairfield and State of Connecticut, have invented certain new and useful Improvements in Pin-Tumbler Locks; and I do hereby declare the following to be a full, clear, and exact description of the invention, such as 10 will enable others skilled in the art to which it appertains to make and use the same.

This invention relates to improvements in pin tumbler locks and more particularly to means for protecting the tumblers and 15 drivers of the same,—the object of the invention being to provide simple and efficient armors for the front portions of the cylinder and plug to prevent access to the tumblers and their drivers by a boring tool inserted 20 at the front of the lock.

With this object in view, the invention consists in certain novel features of construction and combinations of parts as hereinafter set forth and pointed out in the 25 claims.

In the accompanying drawings, Figure 1 is a longitudinal sectional view of a portion 30 of a lock embodying my improvements. Figure 2 is a front view, and Figure 3 is a section on the line 3—3 of Figure 2.

The cylinder shell of the lock is shown at 1 and is adapted for the reception of the plug 2,—the former being provided with bores 3 to receive spring pressed drivers and 35 the plug having bores 4 to receive pin tumblers.

A hardened steel cap 5 is located on the front end of the cylinder and forms in effect a face plate for the latter as well as an 40 armor. The cap or armor 5 is provided on its rear side with lugs 6 which are not hardened. The lugs 6 are formed with bores 7 by drilling and they enter sockets 8 having shoulders 9, in the end of the cylinder shell.

45 After having been inserted in the sockets 8, these lugs are expanded at their rear ends with a suitable tool so as to overlie the shoulders 9 and thus the cap or armor is securely fastened by inaccessible fastening means.

50 The cap or armor 5 is made with an opening 10 in line with the plug and the cylinder shell is provided with an annular flange 11

which enters this opening. The front end of the plug 2 enters the opening 10 in the cap or armor 5 and is provided with a flange 55 12 which overlies the flange 11 on the cylinder shell. The front end of the plug 2 is disposed rearwardly of the plane of the front face of the cap or armor 5 and is provided with a hardened steel armor 13 having 60 an annular flange 14 encircling the flanged portion 12 of the plug within the opening 10 of the cap or armor 5, and said armor plate 13 lies flush with the outer face of said cap or armor 5. 65

It is apparent that with my improvements, it will be impossible to injure the pin tumblers or their drivers with the use of a tool applied to the front end of the lock.

Having fully described my invention what 70 I claim as new and desire to secure by Letters-Patent, is:

1. The combination with a lock cylinder socketed at its end, of a hardened steel armor on the end of said cylinder and having 75 means entering the socket portion of the latter, and securing means for said last-mentioned means.

2. The combination with a lock cylinder having sockets in its end, of an armor cap 80 on the end of the cylinder and provided with projections entering said sockets and rigidly connected with the cylinder.

3. The combination with a lock cylinder having sockets in its end, of an armor cap 85 on the end of said cylinder and provided with projections entering the sockets in the cylinder, and means whereby said projections are secured in the sockets.

4. In a pin tumbler lock, the combination 90 with a cylinder shell, of a hardened steel cap or armor on the front end thereof, and inaccessible fastening means projecting from said cap or armor and into the cylinder and rigidly securing said cap or armor to the 95 cylinder shell.

5. In a pin tumbler lock, the combination with a cylinder shell having sockets, of a hardened steel cap or armor on the front end of said cylinder shell, said cap or armor having unhardened hollow lugs expanded at 100 their rear ends within said sockets.

6. In a pin tumbler lock, the combination of a cylinder shell, a hardened steel cap or

armor on the front end of said shell and having an opening, a plug in the shell and entering the opening in the cap or armor, and a hardened steel armor applied to the front end of said plug and provided with a flange embracing the front end of the plug within the opening in the cap or armor.

In testimony whereof, I have signed this specification in the presence of two subscribing witnesses.

PETER F. AUGENBRAUN.
